APPARATUS FOR RESETTING RAIL ANCHOR
JAWS

Leopold J. Denz, Chicago, Ill., and Arthur Daniels,
South Minneapolis, Minn., assignors, by mesne
assignments, to Poor & Company, a corpora-
tion of Delaware

Application November 23, 1936, Serial No. 112,310

2 Claims. (Cl. 153—21)

This invention relates to apparatus for resetting the jaws of rail anchors, removed from the rails after a long period of service, so that the anchors when re-applied to the rails will take a firm grip thereon.

The principal object of the invention is to provide an improved apparatus for conveniently and accurately resetting the jaw portions of rail anchors, particularly anchors of the type adapted to grip the rails with resilient pressure, whereby the reconditioned anchors may be driven or otherwise re-applied to the rails without danger of spreading the jaws beyond their elastic limits.

According to the present invention, the rail gripping jaws of anchor devices removed from the rails are restored to substantially their original contour by placing the jaw portions of the anchors between clamping elements which exert increasing pressure thereon to bend the jaw portions of the anchors to such positions as will provide a predetermined resilient grip on the rail base when the anchor is driven in a direction to force the jaw portion thereof onto the base flange of a rail. A relatively gradual increase in the application of bending pressure to the anchor jaws, as contemplated by this invention, distributes the bending force over a substantial portion of the anchor jaws and thereby restores the anchor jaws to their original position. The strong and unyielding grip exerted by the apparatus of this invention, makes it practicable to observe the condition of the jaw from time to time as the bending progresses so that the application of pressure can be immediately interrupted when the jaw portions have been bent to the desired position.

A further and more specific object of the invention is to provide a portable apparatus of simple and inexpensive construction which may be moved along a railway track in accordance with the progress of the work being performed by a track repair crew and thereby be readily available for resetting the rail anchor jaws immediately following the removal of the anchors from a rail. To this end the apparatus comprises a hand operated lifting jack or other suitable pressure applying device and a frame structure therefor which are mounted on a track repairman's push car. This arrangement provides a freely movable apparatus which can be moved over the track for long distances without tiring the workmen and which also positions the vertically movable pedestal portion of the jack and the hand operating mechanism therefor at a convenient height for use by a workman standing on

the ground. The pressure applying device, for example the lifting jack shown herein, is such that it is capable of developing relatively high pressure so that a rail anchor device clamped between the movable pedestal of the jack and a stationary abutment of the frame structure can be readily bent without substantial exertion on the part of the workmen. The several parts of the jack and frame structure are of sufficient rigidity to prevent flexing or yielding of the parts during the bending of an anchor device and thereby avoid creating resilient pressure which might otherwise carry the bending of the anchor beyond the limits intended.

Other objects and advantages of the invention will be readily apparent from the following detailed description of one approved form of apparatus embodying the principles of the invention.

In the drawing:

Fig. 1 is a face view in elevation of a portable apparatus constructed in accordance with this invention.

Fig. 2 is a side view in elevation of the structure shown in Fig. 1, and

Fig. 3 is a fragmentary detail view of one form of rail anchor positioned between the clamping elements of the apparatus so that movement of one of the clamp elements toward the other will bend the upper and lower jaws of the anchor in a manner to partially close the space between said jaws.

Referring to the drawing, the apparatus herein shown may be described generally as comprising a movable supporting member 18, a frame member 11 secured to the movable support, a pressure element 12 associated with said frame and said movable support, and means, preferably a hand operated element 13, for operating the pressure element to apply suitable bending pressure to the jaw portions 14-15 of a rail anchor device 16.

The rail anchor device herein shown in connection with the apparatus of the present invention is a well known form of one-piece rail anchor adapted to be driven in the direction of its length into gripping engagement with the base portion of a rail. When the anchor is in its applied position the jaws 14 and 15 exert a resilient grip on the top and bottom surfaces of the rail base flange at one side of the rail and the abutment shoulder at the other end of the anchor engages a vertical edge portion of the rail base at the other side of the rail to maintain the anchor in its applied position. It should be understood, however, that the particular form of anchor device herein shown is used merely

for the purpose of illustration and that the scope of the invention is not intended to be restricted to resetting of the jaws of the particular rail anchor shown.

- 5 The movable support 10 of the present embodiment of the invention is preferably a car adapted to be moved along the rail 17, for example, a push car such as is ordinarily used by a crew of track repairmen.
- 10 Secured to the flooring of the car, preferably near one edge thereof, is a base member 18 on which is mounted the frame member 11. This member preferably comprises a metal strip bent to yoke form with its arms 19-20 extending upwardly. The upper ends of said frame arms are connected and rigidified by means of a U-shaped member 21 which is interposed between and secured to the upper end portions of the arms 19-20 to provide a fixed abutment for the 15 rail anchor during the resetting of its jaw portions.

The pressure applying means 12, illustrated herein, is a portable lifting jack of a type used by railway repair crews and comprises a casing 25 removably positioned on the bottom portion of the frame structure between the arms 19-20 thereof. The said jack member is preferably of the type which is provided with a vertically movable screw 22. Removably secured to the 30 upper end of the screw 22 is a pedestal plate 23, the opposite ends of which are recessed to embrace the frame arm members 19-20. The recesses formed in the ends of the pedestal plate provide guide members 24 which slidably engage 35 the edge portions of the frame arms and thereby maintain the jack and pedestal plate in proper position relative to the abutment member 21. The under surface of the abutment member 21 and the top surface of the pedestal plate 23 are provided with hardened metal wearing plates or 40 pads 25, 26 and 27. These pads are welded to their associated parts of the apparatus and may be of any suitable or desired shape to maintain the anchor device in proper position to insure the 45 application of the bending force in the appropriate direction to restore the jaws of the anchor to their original positions.

As shown in the drawing, the lower jaw 15 of the rail anchor is supported on the pad 26 so that the upper jaw 14 will bear at its inner end 50 only against the wearing pad 25 of the abutment 21. The upward movement of the jack pedestal plate 23 exerts a strong clamping force on the jaws 14-15 of the anchor and thereby forces the 55 jaws toward each other. The bending force is distributed over the curved portion of the anchor which connects the upper and lower jaws and thereby insures proper positioning of the rail engaging surfaces 14a-15a of the anchor jaw to 60 provide the desired fit on the top and bottom surfaces of a rail base flange. In order to avoid imposing unequal strains on the apparatus, the anchor is positioned in the apparatus so that the anchor jaws will bear on the pads 25-26 at 65 substantially equal distances from the vertical center of the screw member 22 of the jack. The frame rigidifying strap members 28 and 29 assist in maintaining the jack structure in a properly centralized position.

70 A revoluble operating shaft 31 extends out of the jack casing and is provided with suitable connections, within the casing, for imparting raising and lowering movements to the screw element 22. The said connections between the shaft and screw are not illustrated herein, since the de-

tails of construction and operation of a jack of the type herein shown, are well known. It is sufficient to state that rotation of the shaft 31 in one direction imparts an upward movement to the screw 22 and pedestal 23 so as to cause the 5 clamping action of the anchor jaws 14-15 between the said pedestal 23 and the abutment 21, as shown in Fig. 3 of the drawing. Rotation of the shaft 31 in the opposite direction imparts a lowering movement to the said screw 22 and 10 pedestal 23 so as to relieve the pressure exerted on the jaw portions of the anchor device. The vertically movable screw 22 will in a manner known, retain any adjusted position without the use of special locking devices to prevent reverse 15 movement of the operating shaft. In other words, the screw 22 and pedestal 23 will remain in any position in which they are moved until that position is changed by positive rotation of the shaft 31.

20 The said operating shaft 31 is rotated by means of a plurality of radially extending arms 32 which are riveted or otherwise suitably secured to a central flange member 33 fixed on the shaft 31. In the drawing, the hand operated 25 mechanism includes four arms 32. It will be obvious, however, that the number of such arms may be increased if a greater number is desired.

In operation, the push car on which the pressure applying mechanism is supported, is placed 30 on a railway track and moved along with the track repair crew. Certain members of the repair crew who are in advance of the push car remove from the rail any of the rail anchor devices which might require resetting of their jaws. 35 The said anchors, when they are removed from the rail, are tossed onto the push car so as to be within easy reach of the workmen having charge of the jaw resetting apparatus. The anchor devices are operated upon to reset their 40 jaws, in the manner hereinbefore described, and are then dropped onto the ground at the rear of the car, where they are re-applied to the rails by other members of the repair crew.

45 By the use of a screw type jack, such as illustrated in the present embodiment, the application of pressure to the anchor is gradual and there is little or no tendency for the power exerted, when the anchor jaws first begin to bend, to surge forward and thereby bend the jaws beyond the limits necessary to restore them to their 50 original positions. The ease with which the screw jack mechanism is operated makes it possible to closely observe the bending of the anchor and to interrupt the bending operation at any 55 time desired.

While the invention is illustrated in one specific embodiment, it will be obvious that various modifications may be made without departure from the principles of the invention. It 60 should be understood, therefore, that the invention is not restricted to the specific form and constructions herein shown and described except insofar as the claims appended hereto are specifically limited.

65 We claim:

1. An apparatus for use in railway track repair work to reset the jaws of rail anchors preliminary to the reapplication of said anchors to the track rails, comprising a frame including a metal strip 70 bent into yoke form and a rigidifying abutment interposed between and secured to the outer ends of the yoke arms, a lifting jack structure removably associated with said frame to provide a clamp assembly adapted to exert non-surg- 75

ing clamping force on bendable portions of a resilient rail anchor to reset the said portions to predetermined positions, and means for portably supporting the said assembly for movement along a railway track in accordance with the progress of the workmen who remove the anchors from the rail and re-apply them.

2. An apparatus for use in railway track repair work to reset the jaws of rail anchors, comprising a supporting structure movably supported on a railway track, a rigid frame secured to said movable supporting structure comprising a U-shaped member and a fixed abutment interposed

between and secured to the sides of said U-shaped member, a portable non-surging pressure applying device positioned in said frame and having hand actuated means for operating the said device, and a movable head slidably engaging the said frame and interposed between said pressure applying device and the fixed abutment of the frame, whereby the said abutment and said head provide clamping jaws for exerting bending pressure on the jaw portions of a rail anchor positioned between them.

LEOPOLD J. DENZ.

ARTHUR DANIELS.
